(57) **CLAIM**

The ornamental design for a universal remote control, as shown and described.

DESCRIPTION

FIG. 1 is a top perspective view of a universal remote control showing my new design;

FIG. 2 is a top plan view thereof;

FIG. 3 is a bottom plan view thereof;

FIG. 4 is a right side elevational view thereof, left side elevational view being a mirror image thereof;

FIG. 5 is a front elevational view thereof; and,

FIG. 6 is a rear elevational view thereof.

The broken lines provided in the above views are used to indicate environmental structure and form no part of the claimed design.
